TEA WAGON

Jerome Warshawsky, Brooklyn, N.Y.

Application December 19, 1958, Serial No. 53,837

Term of patent 7 years

(Cl. D33—14)

FIG. 2

Fig. 1 is a front perspective view of a tea wagon showing my new design; and

Fig. 2 is a rear perspective view thereof.

I claim:

The ornamental design for a tea wagon, as shown.
